UNITED STATES PATENT OFFICE

RUDOLPH A. SKRIBA AND FREDERICK J. LITTELL, OF CHICAGO, ILLINOIS, ASSIGNEES
TO F. J. LITTELL MACHINE CO., OF CHICAGO, ILLINOIS, A CORPORATION OF ILLINOIS

AUTOMATIC RIVETING PRESS

Application filed November 7, 1928. Serial No. 317,861.

This invention relates to automatic riveting presses of the kind in which rivets are fed successively to a point on a work support at which they may be received in a structural member to which they are to be riveted, and in which it is desirable to have means for arresting the rivet at the end of its throw in accurately predetermined position that will insure its encounter by the riveting plunger; and in which, also, it is desirable to have means for promptly and automatically displacing the structural member upon completion of the riveting operation in order to clear the rivet channel for the succeeding rivet and in which displacement it is necessary that the rivet arresting means yield the rivet to displacement along with the structural member.

The object of the invention is to provide means for realizing the functions above set forth. Accordingly, one feature of the invention consists in providing in a channel through which rivets are fed to a riveting point, means, preferably a spring pressed jaw, which will arrest the movement of the rivet upon arrival at the riveting point and hold it there accurately in position while a structural member through means of a prepared hole is engaged over a protruding end of the rivet, but which holding means will yield to abnormal displacing force applied to the rivet so that the rivet after being united to the structural member may continue its movement until it emerges from the channel. And another feature of the invention consists in mounting upon the press a kick-off lever or levers fulcrumed in position to swing past the work support and impart displacing movement to the structural member, so that it will carry the rivet along with it at the proper interval of time in relation to the movement of the press plunger; the preferred embodiment of this part of the invention involving the use of a bell crank lever, or a lever with a lateral offset, for the kick-off means; a pick up hook traveling in a path which causes it to engage the offset of the kick-off lever and which has bodily movement in a direction to cause the kick-off lever to swing past the work sup-

port; a spring for returning the kick-off lever; a spring controlling the pick up hook (preferably through means of an offset on said hook); and a stop for tripping the pick up hook, located in the path of bodily movement of the hook (and preferably in the path of the offset of the hook); said stop being adjustable in the path of its action, and there being preferably an adjustable limiting screw for the kick-off lever.

Still another feature of the invention consists in providing a broad flat work engaging table, and in conducting the rivets from the point of discharge from the rivet chute to the position at which they are inserted in the workpiece in such a manner that they do not project above the surface of the table. By means of such a provision, the table is at all times free to receive and properly support the work without danger of the edge of the workpiece catching upon exposed rivets and jamming the machine, or of exposed rivets interfering with the proper positioning of the workpiece upon the table.

In the accompanying drawings, in which the preferred embodiment of the invention is shown by way of illustration—

Figure 1 is a side elevation of those portions of a punch press with which the invention is immediately concerned.

Figure 2 is a front elevation of the same.

Figure 3 is a plan view of the lower portion of the press including the work support and the means for feeding and holding the rivets, the standards of the press being shown in section.

Figure 4 is a detail view of a portion of Figure 3 on an enlarged scale; and

Figure 5 is a front elevation of the parts shown in Figure 4.

1 represents a bed, 2 a work support, 3 a rivet feeding channel leading to the work support, 4 a rivet feeding slide, 5 a riveting die, and 6 a vertically reciprocating press plunger in which the riveting die 5 is mounted.

The rivet channel 3 may have an intake port 3a, and the rivet feeding slide 4 may be operated by the lever 7 moved in one direction by spring 8 and in the opposite di-

rection by cam 9, as fully set forth and claimed in our copending application, Serial No. 300,240, filed August 17, 1928. Rivet receiving port 3a may be connected with a rivet chute 3b leading from any suitable source of supply, for instance, that shown in the said copending application.

As will be seen from an inspection of Figure 1, the rivet channel 3 is inclined in an upward direction as it approaches the riveting die 5, and the depth of the channel and its degree of inclination are such that when rivets enter the receiving port 3a they are located entirely beneath the surface of the flat work-engaging table, and continue to be located beneath the table as they are advanced until they are moved into a riveting position. With such a provision, a large piece of material may be disposed upon the work-engaging table and permitted to remain thereon during the insertion of successive rivets without interfering with the feeding of the rivets from the receiving port 3a across the table to a position beneath the riveting die 5.

In order to arrest rivets, such as X (Figures 3, 4, and 5) at the work support and properly spot them in position to receive the riveting die 5, but yieldingly arrest the rivets so that they may continue their passage out of the rivet channel when the riveting is completed, said channel is provided with a jaw 10 pivoted at 11 and pressed normally in rivet-gripping position by means of spring 12; said jaw being incorporated in one lateral confine of the rivet channel 3 in such position that it will grip the rivet against the opposite wall of the channel; and said jaw being concaved, as shown at 10a (Figure 4) and having its concavity so presented that it will prevent the rivet from passing on out of the channel 3 by the momentum of the rivet under the forward stroke of the slide 4, and at the same time will meet the surface of the rivet at an angle to the line of rivet movement sufficiently less than the slipping angle to prevent extruding the rivet backwards. Through this means the rivet is held and spotted beneath the die 5 with sufficient stability to adapt the upwardly protruding end of the rivet X' (Figure 5) to serve as a spotting pin or feeler for the prepared opening in the structural member Y that is to be riveted.

In order that the structural member Y, together with the secured rivet X may be automatically displaced from the work support immediately the riveting is completed, and so make way for the next ensuing rivet that is automatically advanced, a kick-off lever 13, preferably in duplicate or dual form as shown in Figure 2, is mounted upon stationary fulcrum 14 which, as shown in Figure 2, constitutes a pair of stub shafts mounted in hangers 15 bolted at 16 to fixed

portions of the press, from which fulcrums the levers 13 depend in position to sweep past the work support 2 in their lever action. These levers 13 are controlled in one direction by spring or springs 17 and in the opposite direction by means of pick-up hooks 18 pivotally mounted at 19 upon the plunger 6, and therefore having bodily movement in a path which causes them to encounter offsets 13a extending laterally from the kick-off levers 13 and in coincidence with the up and down movements of said plunger; said pick up hooks having lateral offsets 20 through which pivotal movements are imparted to the hooks upon their pivots 19, namely, by springs 21 in the direction to cause engagement of the kick-off lever, and by hook-tripping stops 22 in the direction to cause the hooks to release the kick-off levers. Stops 22 are mounted in brackets 23 on the fixed standards 24 of the machine and in the path of the hook offsets 20, so that when the plunger 6 is moved upward a distance to impart the desired range of swinging movement to kick-off levers 13, hook offsets 20 will encounter the stops 22 and release the levers 13 to their return movement under the influence of springs 17. 25 represents arresting stops for the levers 13 for limiting rearward movement of the latter. Stops 22 and 25 are vertically adjustable so that the range of movement of the kick-off levers 13, within necessary limits, may be varied at will to suit different forms or dimensions of structural members 5 that have to be riveted.

While we have shown and described the kick-off lever as a dual or twin construction, and have duplicated the actuating and controlling elements coordinated therewith, it is obvious that the structural, functional, and cooperative conditions identifying this part of the invention might be realized by unitary elements of like construction and operation.

While we have, for purposes of illustration, shown and described the best embodiment of the invention now known to us, it is to be understood that the invention may be embodied in other physical forms within the terms of the subjoined claims.

We claim:

1. In a riveting press, a reciprocating plunger, a work support, a kick-off lever having a fulcrum located to cause the lever to swing against and displace a structural member from said work support and out of the path of said plunger, and a lever actuating means carried by the plunger imparting movement to the kick-off lever.

2. In a riveting press, a reciprocating plunger, a work support, a kick-off lever having a fulcrum located to cause the lever to swing against and displace a structural member from said work support, and lever

actuating means imparting movement to the lever in timed relation to the movement of the plunger; said lever actuating means comprising a hook; said kick-off lever having an offset portion extending into the path of said hook; and there being a trip stop in the path of and adapted to displace said hook.

3. In a riveting press, a work support, 10 a plunger reciprocating to and from said support, a kick-off lever fulcrumed in a plane above the plane of the support and adapted to swing past the support, an offset extending from said lever, a pick up hook receiving an upward impulse in timed relation to the movement of the plunger and adapted to engage said offset, and a trip stop in the path of said pick up hook.

4. In a riveting press, a work support, a 20 plunger reciprocating to and from said work support, a kick-off lever having an offset, a pick up hook having an offset moving in timed relation to a movement of the plunger and adapted to engage said kick-off lever, 25 and a trip stop in the path of the offset of said hook adapted to displace the hook from engagement with said kick-off lever.

5. In a riveting press, a work support, a 30 kick-off lever movable past said work support, a pivoted pick up hook bodily reciprocating in a path that causes it to engage and impart swinging movement to said lever, said pick up hook having an offset, and a hook-tripping stop in the path of movement of said offset adjustable in said path to vary the time of tripping.

6. In a riveting press, a work support, a 40 plunger moving to and from said support, a kick-off lever movable past said work support, a pivoted pick up hook mounted upon and bodily reciprocating with said plunger in a path that causes it to engage and impart swinging movement to said lever, a spring moving said pick up hook into 45 engagement with said kick off lever, an offset on said pick up hook, and a hook-tripping stop in the path of movement of said hook offset.

Signed at Chicago, Illinois, this 1st day 50 of November, 1928.

RUDOLPH A. SKRIBA.
FREDERICK J. LITTELL.
